US0D1006617S

(12) **United States Design Patent** (10) **Patent No.:** **US D1,006,617 S**
(45) **Date of Patent:** **** Dec. 5, 2023**

(54) **PACKAGE**

(71) Applicant: **Apple Inc.**, Cupertino, CA (US)

(72) Inventors: **Anthony Michael Ashcroft**, San Francisco, CA (US); **Richard P. Howarth**, San Francisco, CA (US); **Peter Russell-Clarke**, San Francisco, CA (US)

(73) Assignee: **Apple Inc.**, Cupertino, CA (US)

(**) Term: **15 Years**

(21) Appl. No.: **29/861,956**

(22) Filed: **Dec. 5, 2022**

Related U.S. Application Data

(63) Continuation of application No. 29/832,647, filed on Mar. 29, 2022, now Pat. No. Des. 971,723, which is a continuation of application No. 29/822,546, filed on Jan. 10, 2022, now Pat. No. Des. 950,374, which is a continuation of application No. 29/682,948, filed on Mar. 8, 2019, now Pat. No. Des. 940,552.

(57) **CLAIM**

The ornamental design for a package, as shown and described.

DESCRIPTION

FIG. 1 is a top front perspective view of a package showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the figures show portions of a package that form no part of the claimed design.

1 Claim, 5 Drawing Sheets
